UNITED STATES PATENT OFFICE.

JACOB E. BRADFORD, OF RIPLEY, OHIO.

COMBINATION-PADLOCK.

1,096,593.

Specification of Letters Patent. Patented May 12, 1914.

Application filed July 10, 1911. Serial No. 637,733.

To all whom it may concern:

Be it known that I, JACOB E. BRADFORD, citizen of the United States, residing at Ripley, in the county of Brown and State of Ohio, have invented certain new and useful Improvements in Combination-Padlocks, of which the following is a specification.

This invention relates to improvements in a combination padlock and more specifically 10 to mechanism for positively holding a locking bolt in set position.

The object of my invention is to provide a simple, inexpensive, and highly efficient combination padlock constructed of a minimum 15 number of parts, and having on its outer surface a single actuating disk.

A further object of my invention consists in a combination with a locking bolt carried within a padlock of a rotatable member for 20 reciprocating said bolt, together with means for retracting said rotatable member when the dial disk mounted at the outside of the padlock shall be given a suitable number of turns or revolutions determined by the secret 25 word or words controlling the revolution of the dial.

With these and other advantages in view my invention comprises the combination, arrangement, and details of construction 30 clearly shown in the drawings, and then more particularly pointed out in the appended claim.

In the drawings Figure 1 is a vertical elevation of my combination padlock held in 35 operative position in a hasp and staple device. Fig. 2 is a sectional elevation of my padlock on the line $x-x$ of Fig. 3. Fig. 3 is a vertical elevation of Fig. 1 with the top removed, showing the internal mechanism thereof. Fig. 4 is a detailed view of a 40 rotatable disk engaging the lever to which the locking bolt is suitably connected. Fig. 5 is a detail sectional view of the padlock wherein is shown the plurality of revolvable 45 disks. Fig. 6 is a sectional transverse view on the line $y-y$ of Fig. 3, and Fig. 7 is a detail sectional view on line $a-a$ of Fig. 3 of a guiding member through which a locking bolt projects to hold the shackle of the 50 lock in set position.

Reference being had to the drawings wherein similar reference characters designate similar parts in the respective views, the novel combination padlock is shown 55 composed of a cylindrical bottom body portion 1 and a top cylindrical portion of the

same diameter 2, between which members 1 and 2 is suitably fastened a band 4 flush with the periphery of said members inclosing a space 3 for the reception of the various 60 parts of the mechanism. The band 4 carries a shackle or locking member 5 suitably pivoted thereto at 6 which is formed at 8 with a recess or notch for the reception of the locking bolt 16 and also has the terminal 65 projection 7 intended to engage a similar formation 7¹ upon the band 4 in overlapping relation. The shackle 5 is shaped to the contour of the band 4 and will be flush exteriorly therewith when held in locking position by said locking bolt.

9 designates a spacing or guide member which, as shown in Fig. 3, is semi-cylindrical in shape with the exception of an inwardly extending curvilinear offset 10 forming an 75 opening adapted to register with a similarly shaped opening in the body portion 1. The member 9 is formed with spaced-apart prongs 11 which engage corresponding notches 12 formed in the body portion 1 so 80 as to occupy the position shown in Fig. 3 and so that the opposite free ends thereof, will at all times, bear against the immovable walls of the band 4; the member 9 is also formed with an opening 9¹ for the passage 85 therethrough of the locking bolt. The member 9 forms a seat upon which the shackle rests when in locked position. A plurality of screw bolts 14 are mounted on the body portion 1 and project above the band 4, 90 which bolts engage corresponding openings in the top plate 2 and are suitably fastened thereto. On either side, preferably, and adjacent the inwardly extending offset 10 of the guide member 9 are alining studs or 95 stops 15 between which is slidably mounted a locking bolt 16, said locking bolt carrying two inwardly extending stops 17 between which is suitably guided an upstanding stud 22 carried at one end of a tilting lever 19 100 pivoted at 20 and carrying at its free end a similar upstanding stud 21, said lever arranged to advance or retract the locking bolt 16 between the guide members 15. The locking bolt 16 is formed at one end with a 105 tongue 18 adapted to project through the opening 9¹ in the guiding member 9 and take into the recess 8 in the shackle 5. It will be noticed that a plurality of washers 30^a are interposed between the tumbler disks, 110 one of said washers being interposed between the top and bottom of said housing.

In order to actuate the lever 19 to move the locking bolt 16 in and out of operative position suitable means are provided, and as shown, consists of a plurality of spaced-apart disks preferably of equal diameter which are all revolvably mounted upon a common pivot 34¹ projecting through the top plate 2 for the purpose of carrying the marked dial 34 to be hereafter described. Reference being had to Fig. 5 it will be seen that the disks are designated 25, 28, and 31, the disk 25 carrying at its top and bottom lugs 26 and 27 respectively at opposite sides of the center; the disk 28 therebeneath carries a top and bottom lug designated 29 and 30 respectively; while the bottommost disk 31 carries at its top a lug 30¹. The top disk 25 is formed with a recess 25¹, the disk 28 is formed with a similar recess 26¹, while the disk 31 has a recess 31¹.

The top plate 2 is formed with a counter-sunk opening 33 within which is adapted to snugly fit a milled dial 34, said dial being pivoted on the reduced end 32 of pivot 34¹ and said opening 33 being so disposed that the dial 34 will have part of its circumference extending outwardly therefrom to assist the user in turning the same on said reduced end 32. A suitable washer 35 is mounted upon reduced end 32 and rests upon the dial 34. The dial 34 has marked or otherwise printed thereupon a circumferentially extending series of letters of the alphabet shown at 36. The said dial is milled to enable the user to rotate it and a lug 37 projects from the bottom of said dial 34 through opening 33¹ to engage with the lug 26 carried by the rotating disk 25.

38 is a fixed pointer coöperating with the rotating milled dial 34 to assist in designating the desired mark upon said dial; each letter of the alphabet marked upon the dial 34 is arbitrarily selected and is spaced from a mark, all of said marks arranged to set off similar intervals around the circumference of the dial so that any of the said marks can be brought in alinement with the pointer 38.

The hasp member 39 is secured by passing the shackle 5 of the padlock through a staple 40 as shown in Fig. 1.

The arrangement of the interengaging lugs upon the tumblers is such that a given tumbler will have to be moved in a given direction in order to occupy a given position where its lug will come within range of the coöperating lug on the next disk so that it may control the direction of movement of the tumbler concerned by moving its lug; however the relative movements of the tumblers will be in opposite directions before the notches formed in them will be in alinement to enable the shackle to be released, as it follows that each lug is in turn actuated by a follower lug and actuates the lug with-

in whose range it is moved. The arbitrary letters marked upon the dial 34 rotatable on the top plate 2 are intended to spell a given name or names and, as known to those skilled in the art, each consecutive letter in the name must be brought in alinement with the pointer 38 and will determine the intervals of movement of the dial 34, it being understood that each padlock will preferably be trued to a different name. As the dial 34 is moved, the lug 37 carried thereby will, in due time, engage lug 26 upon the top of the disk 25. In locked position the outer end of the locking bolt lies in the recess 8 of the shackle 5, and the projection 7 of said shackle will thereby interlock with the corresponding member 7¹ of the band 4; stud 21 upon lever 19 will at the same time bear upon the peripheral surface of each of the disks 25, 28, and 31 since the recesses 8 formed in all of said disks are normally out of alinement. The object of rotating the dial 34, step by step determined by the consecutive letters of a name is to cause the lugs upon each dial to interengage, one after the other until all the recesses of the disks have been brought into alinement, and then the spring-pressed stud 21 of lever 19 will be caused to enter said recesses thereby tilting lever 19 and as the dial 34 completes its movements, said lever will move bolt 16 out of recess 8 to enable the shackle to be disengaged.

The operation of the lock is extremely simple and easy to understand and is as follows: The dial 34 is rotated in first one direction and then another until the depending lug thereon through the medium of the various lugs on the disks has caused the recesses of the several disks to aline to admit the stud 21 on the lever 19 which lug is pressed toward said recesses by the spring 23. When said stud is in said recesses a turn of the dial will rotate all of the disks simultaneously and by means of said stud 21 throw the end of the lever having said stud thereon in such a direction that its other end, having the stud 22 seated between the members 17 on the lock bar 16, will slide said bar inwardly when unlocking the device and cause it to withdraw from the recess in the shackle whereby the said shackle is released from its locked position. The stud 21 is cylindrical and slightly smaller in circumference than the recesses 8 in the disks, consequently when the disks are rotated toward the hinged portion of the shackle, the recesses in the disks traveling in a circular path and the stud 21 mounted on the lever 19 pivoted at 20 moving in an opposing circular path will naturally become disengaged leaving the disks free to travel independently of one another whereby the stud 21 will be held against the peripheral edges of said disks and con-

sequently the end 18 of the lock bar 16 is brought into engagement with the recess 8 in the shackle whereby the device will be held locked.

5 While I have shown the details of constructions now best known to me I do not wish to be limited strictly thereto for numerous modifications may be resorted to falling within the spirit of the appended 10 claim.

I claim—

In a device of the kind described, in combination, a housing, said housing being formed with a cylindrical opening at its 15 top having its circumference tangent to the periphery of said housing, a vertical stud disposed in the bottom of said casing and having a reduced end, a plurality of washers mounted on said stud in spaced 20 apart relation, a plurality of disks loosely mounted on said stud between said washers,

each of said disks being formed with a similarly-sized notch, each notch having opposite rounded edges, a relatively large disk plate loosely mounted on the reduced end of said stud and disposed flush with the top of said housing, a lever arm fulcrumed on the bottom of said housing, a pin carried by said lever arm, a depending pin carried by said large disk plate 30 and projecting through an opening in said housing, inter-engaging pins carried by said other disks, and a spring arranged to press against the pin carried by said lever arm.

35 In testimony whereof I affix my signature in presence of two witnesses.

JACOB E. BRADFORD.
